US0D1106444S

(12) **United States Design Patent** (10) **Patent No.:** **US D1,106,444 S**
(45) **Date of Patent:** **** Dec. 16, 2025**

(54) **OCULAR INJECTOR**

(71) Applicant: **EyePoint Pharmaceuticals, Inc.**,
Watertown, MA (US)

(72) Inventors: **Evan Williams**, Boston, MA (US);
Michael W. Metz, Providence, RI (US)

(73) Assignee: **EyePoint Pharmaceuticals, Inc.**,
Watertown, MA (US)

(**) Term: **15 Years**

(21) Appl. No.: **29/954,593**

(22) Filed: **Jul. 28, 2024**

7,468,065 B2 12/2008 Weber et al.
7,476,217 B2 1/2009 Martin et al.
D592,746 S 5/2009 Highley et al.

(57) **CLAIM**

The ornamental design for an ocular injector as shown and described.

DESCRIPTION

FIG. 1 is a top front perspective view of an ocular injector showing the claimed design;

FIG. 2 is a bottom rear perspective view thereof;

FIG. 3 is a left side view thereof;

FIG. 4 is a front view thereof;

FIG. 5 is right side view thereof;

FIG. 6 is a rear view thereof;

FIG. 7 is a top view thereof; and,

FIG. 8 is a bottom view thereof.

The broken lines in the figures show portions of the ocular injector that form no part of the claimed design.

1 Claim, 5 Drawing Sheets
